UNITED STATES PATENT OFFICE.

HARRY WILLIAMS CHARLTON, OF OTTAWA, ONTARIO, CANADA.

FARE-COLLECTING BOX.

No. 918,963.

Specification of Letters Patent.

Patented April 20, 1909.

Application filed May 18, 1907. Serial No. 374,506.

To all whom it may concern:

Be it known that I, HARRY WILLIAMS CHARLTON, of the city of Ottawa, in the county of Carleton, Province of Ontario, 5 Canada, have invented certain new and useful Improvements in Fare-Collecting Boxes; and I do hereby declare that the following is a full, clear, and exact description of the same.

10 My invention relates to improvements in fare collecting boxes, and the objects of my invention are to provide an exceedingly cheap and simple form of fare collecting box, which will register the number of fares taken 15 and from which, it will be impossible to extract a fare, after it has once been registered, a further object being to leave the ticket in the sight of the passenger or purchaser, until it is finally dropped into the larger containing receptacle, the details of the construction and the features of novelty therein, being fully set forth and described in the accompanying specification and drawings.

In the drawings, Figure 1 is a vertical sectional view through a fare collecting device. Fig. 2 is a vertical sectional view through the rotary carrying member in its rotated position. Fig. 3 is a sectional view along the line 2—2, Fig. 2. Fig. 4 is a sectional detail of the locking plunger. Fig. 5 is a perspective view of the rotary carrying member. Fig. 6 is a top view of the box with a portion broken away. Fig. 7 is a sectional view along the line 3—3, Fig. 6. Fig. 8 is 30 a vertical sectional view through the rotary carrying member with the box in its inverted position.

In the drawings like characters of reference indicate corresponding parts in each figure. 40 A is the main portion of the box, or receptacle in which the tickets, after collection, are held. It is provided with a suitable handle *a*. Secured to the top of the box and extending through an aperture therein is a 45 cylindrical casing *B* held in position by suitable means, those shown being flanges *b* and *c* which are bolted to the box. The ends of this cylinder are closed by caps *d* and *e* which, when removed, permit of free access to the 50 interior of the same.

C is the cylindrical rotary carrying member located within the casing *B* and having an operating lever *f* secured thereto and extending through a slot *g* in the casing by 55 means of which the rotary member may be partially rotated. This rotary member is

made of some transparent substance, such as glass, and the front of the casing *B* is provided with a slot *h*, through which the ticket in the rotary member may be observed. 60 The ticket may be further observed through the slot *g*.

i is the carrying slot, which extends through the rotary member, the top of which normally registers with the slot *h*, 65 whereby the ticket may be freely inserted therein.

The opposite end of the slot is adapted to register with a slot *j* in the casing, when the rotary member is rotated to the greatest 70 extent permitted by the length of the slot *g*. The position of the slot *i*, in this case, will be substantially vertical and the top of it will be closed by the top portion *k* of the casing.

The rotary member is held, normally, in 75 the position shown in Fig. 1, by means of a compression spring *l* extending around an arc-shaped guide rod *m* secured to the rotary member and located within a recess *n* provided therein, the opposite end of the guide 80 rod extending through a lug *o* secured to the casing, and which is also abutted by the end of the compression spring. The compression spring thus abuts the lug at one end and the side of the recess *n* at the other end and normally resiliently holds the rotary member in 85 position with the slot *i* registering with the slot *h* in the casing.

To prevent the fares being extracted by an inversion of the box and a reversal of the 90 movement of the carrier member, I provide a locking device *D*, which is adapted to automatically lock the rotary member when the box is inverted. This consists of a casing *p* divided by partitions into three compartments *q*, *r* and *s*, in which are located locking 95 plungers *t*. As shown in Fig. 4 these locking plungers have sets of ratchet teeth *u* and *v* provided on their edges and the opening *w* in the top of the compartment is constricted 100 until it is equal to the greatest diameter across the teeth, whereby after the plungers slide partially out, it will be necessary to shake the box laterally, in order that the plungers may be moved in by a step-by-step 105 movement, the teeth on opposite sides being alternately engaged. To further assist in this locking of the plungers in their outward position, I provide two additional teeth *x* and *y* on the bottom thereof, which are adapted to 110 engage sets of ratchet teeth 5 and 6, formed on the side of the casing. The casing *p* is

secured to the casing B and a slot 7 is provided in the latter, through which the plungers may operate to engage the rotary member. I prefer to effect this engagement 5 with the rotary member by means of a recess 8 in the rotary member, into which the plungers are adapted to take when the rotary member is in the position shown in Fig. 2, the bottom 9 of said recess being provided 10 with a number of steps to correspond with the number of plungers, whereby if even two of the plungers fail to slide outwardly, the third one would engage its proper step or shoulder, and thus prevent the backward 15 rotation of the rotary member.

To register the fares as they are taken, I provide a cyclometer E, of any well known construction, which is located within a recess in the rotary member and has the operating 20 wheel 10 thereof, extending in an arc-shaped slot 11, where it is adapted to be intermittently engaged by a screw-threaded tappet pin 12, which is adjustably held in a lug 13 secured to the casing. By this means, each 25 time the rotary member is oscillated a fare is registered, the backward movement of the rotary member being compensated for within the cyclometer, according to the well known operation of these instruments.

30 The face 14 of the cyclometer is so disposed that the reading thereon may be observed through the slot *h* in the casing.

In order to prevent the attendant operating 35 the box from observing the operation of the locking mechanism thereof, and in order to make the ticket more clearly visible, I coat the interior of the recesses *n* and 8 with a suitable reflecting compound, such as is usually employed in mirrors and I further 40 nickel plate the whole of the inside surface of the casing, or otherwise impart to it reflecting qualities.

In the operation of the device, the ticket or 45 tickets are inserted by the passenger in the slot *i*. The conductor then compresses the lever *f* and rotates the rotary member until the slot *i* registers with the discharge slot *j* in the casing when the tickets drop into the inner receptacle. Should the conductor attempt 50 to invert the box and thus bring the tickets again into the slot *i*, the locking plungers *t* fall outwardly and engage the steps 9 in the recess 8 and in order to free the plunger from this engagement it is not only necessary to invert the box, but also to shake it considerably laterally. This lateral shaking serves to cause any tickets which may have 55 fallen into the slot *i* to drop out of the same into the larger receptacle and hence when the rotary member is free and does rotate to its original position under action of the spring *m*, there will be no tickets in it.

The registering device registers each rotation 60 of the rotary member and if three tickets are inserted at one time it would be necessary,

after these have been discharged into the larger receptacle, to rotate the rotary member twice again, in order that it might register the correct number of fares taken.

The carrying cylinder being transparent, 70 enables the ticket to be perceived both by the passenger and by the conductor, the latter thus being given an opportunity to insure that it is of the proper character.

The use of the cyclometer has the additional 75 advantage that it serves as a convenient means to gage the traffic on a given line during any determined period. It further enables the actions of the conductor to be closely checked, as it would be a very simple 80 matter to obtain the readings of the cyclometer at different periods and determine whether they corresponded with the number of passengers who have entered during that period. In certain cases, it might be desirable 85 to dispense with the use of the cyclometer, in which case the recess in which it is located, may either be filled up or used as a space to contain advertisements.

The use of the box is not limited to collecting 90 street car fares, as it will be found useful in refreshment stands, restaurants, bread wagons, milk wagons, and all places where anything is sold for one price, or a multiple of that price and where the business 95 is not directly under the supervision of the owner. In using the box it will be necessary to observe that the tickets should be of uniform size and must be separated before insertion. If two kinds of tickets are observed, such as adults' and children's, it will be necessary to have these clearly distinguished by color or other suitable means, as each one will register as a whole fare.

While the invention has been described 105 herein, with great particularity of detail, yet it will be readily understood that in carrying out the construction of the same, changes might be made in the details, thereof, without materially departing from the spirit of 110 the invention.

What I claim as my invention is:—

1. In a fare box, a rotary conveying member having a slot therethrough, a casing inclosing the same having two slots therein, 115 through which the tickets are adapted to be inserted and discharged, the said slots being so arranged that they cannot simultaneously register with the slot in the rotary member, a receptacle to which the casing is secured 120 and into which the tickets are adapted to be discharged, and resilient means for normally holding the rotary member with the slot therethrough registering with the slot in the casing through which the tickets are 125 adapted to be inserted, as and for the purpose specified.

2. A fare box including, in combination, a rotary conveying member having a slot therethrough, a casing inclosing the same, 130

having two slots therethrough, adapted to register at different points with the slot in the rotary member, a projecting lug in the casing, an arc-shaped guide rod secured to

5 the rotary member and located in a recess in the same and extending through the lug, a compression spring extending around the guide rod and abutting at one end the lug and at the other, the side of the recess in
10 the rotary member, as and for the purpose specified.

3. In a fare collecting box, the combination with the transparent rotary member having a recess therein and operating means

15 within the recess, a casing partially inclosing the rotary member, of a coating of reflecting material covering the inside of the recess adapted to obscure the mechanism within the same, as and for the purpose specified.

20 4. In a fare collecting box, the combination with the rotary carrying member, and locking means therefor automatically operated when the box is inverted, and means for preventing the disengagement of the locking
25 means releasable only by the inversion and lateral shaking of the box, as and for the purpose specified.

5. In a fare collecting box, the combination with the rotary member, of a freely slideable locking plunger adapted to engage the same when the box is inverted, and locking means preventing disengagement of the plunger releasable by lateral shaking of the box, as and for the purpose specified.

35 6. In a fare collecting box, the combination with the rotary conveying member, of a freely slideable plunger having a ratchet tooth thereon, a casing inclosing the same and having corresponding teeth adapted to be engaged by the teeth on the plunger after the same is moved outwardly and thus prevent retrograde movement, as and for the purpose specified.

40 7. In a fare collecting box, the combination with the rotary member, of a plunger having teeth on the sides thereof, a casing for the same having a constricted opening equal in width to the greatest width of the plunger, the edges of which are adapted to be engaged by the teeth on the plunger, as and for the purpose specified.

45 8. In a fare box, the combination with the rotary member, of a plunger having teeth on the sides and ends thereof, a casing inclosing the plunger having a constricted opening, the edges of which are adapted to be engaged by the teeth on the side of the plunger and also

having teeth on the inside adapted to be engaged by the teeth on the end of the plunger, the said teeth being adapted to be disengaged from each other by the lateral shaking of the fare box, when in its normal position, as and for the purpose specified.

9. In a fare collecting box, the combination with the rotary carrying member and means for supporting the same, of a plurality of locking plungers operated when the box is inverted and separate shoulders on the rotary member, adapted to be engaged by each of the plungers, as and for the purpose specified.

10. In a fare collecting box, the combination with the transparent rotary carrying member, of a casing partially inclosing the same, leaving open spaces through the top, by means of which the ticket may be observed, the inside surface of the casing being of a light reflecting character, as and for the purpose specified.

11. A fare collecting box, including in combination, a transparent rotary conveying member, having a slot therethrough, a casing partially inclosing the same having slots therein adapted to register at different times with the slot through the rotary member, and a locking device automatically operated by inversion of the box when the rotary member has been rotated to its discharging position, as and for the purpose specified.

12. A fare collecting box, including in combination, a transparent rotary member, having a slot therethrough, a casing partially inclosing the same and having two slots therein, for the entrance and discharge of the tickets, the said slots being adapted to register at different times with the slot through the rotary member, resilient means for holding the rotary member with the slot therethrough in engagement with the entrance slot through the casing, a plurality of locking plungers automatically operating to lock the rotary member when the box is inverted, with the slot in the rotary member registering with the discharge opening in the casing, and a receptacle connected to the casing, into which the tickets are adapted to be discharged, as and for the purpose specified.

Signed at Ottawa, in the Province of Ontario, this 9th day of May, 1907.
